UNITED STATES PATENT OFFICE

JACOB J. KOGAN, OF LOS ANGELES, CALIFORNIA, ASSIGNOR TO UNION OIL COMPANY, OF CALIFORNIA, OF LOS ANGELES, CALIFORNIA, A CORPORATION OF CALIFORNIA.

AUTOMATIC PRESSURE RETAINER FOR GAS LIFT WELLS

Application filed July 16, 1929. Serial No. 378,802.

This invention relates to methods and devices adapted to be used in oil wells operating by the so-called air and gas lift methods, for automatically retaining the pressure in the event of a substantial or complete drop of said pressure at the source of supply.

In operating by gas and air lift methods a flow tube is commonly used which depends into the well casing and from which the oil and gas mixture is expelled by the pressure of the introduced gas. In installations heretofore used for operation of oil wells by air and gas lift methods, when the compressor, for example, would stop or idle without receiving any air or gas ejection of oil from the tubing would stop, and, since there is then no pressure in said tubing, oil would accumulate in the latter to such a height that an excessive pressure would have to be introduced into the casing from the source (for example the compressor) to raise this accumulated column of oil to the surface.

It is the object of this invention to provide a method which, in the event of a drop of pressure at the source of supply, will automatically retain the pressure in the well tubing so that this latter will prevent a further inflow of oil into the tubing, thus facilitating the automatic starting of the flow of fluid from the well when the pressure of the air or gas passing into the casing from the source again rises to a certain predetermined value.

Broadly stated, the invention resides in operating with a device which will automatically close a valve on the tubing (or a prolongation thereof) when the pressure of the air or gas in the pipe-line leading from the source of supply to the casing has dropped below a certain predetermined value, and which will automatically open said valve as soon as the pressure rises to a predetermined point in the aforesaid pipe-line.

In one form, the invention comprises a source of gas pressure, means controlled by said pressure for holding the valve in open position while a predetermined pressure is maintained in a line leading from the source of supply to the well, and means for automatically closing the valve when a complete or

substantial drop in said pressure occurs, the latter means permitting an automatic opening of the valve when the pressure in the said line rises to a certain value.

The pressure controlled means in a practical embodiment comprises a chamber or a container, a piston or similar device connected to the stem of the valve provided in the flow tubing, and a connection for applying the pressure to the piston. The invention further comprises an auxiliary control, such as a detent or other means, positioned to prevent the opening of the valve, when once closed, until a certain predetermined pressure higher than normal operating pressure is obtained in the casing and in the line leading to it.

Referring to the accompanying drawings which disclose preferred embodiments of the invention by way of illustration:

Fig. 1 is a vertical longitudinal section through one form of the device;

Fig. 2 is a chart showing the fluctuation of the pressure in the casing during the operation of the preferred form of the device;

Fig. 3 is a diagrammatic view partly in section of another form of the device.

As shown in Fig. 1 the body of the chamber is made of an internally ground cylindrical pipe 10 threaded externally at the ends to receive the threaded caps 11 and 12. A piston comprising a cup-leather 13 held between two plates 14 and 15, moves in the cylinder 10. A diaphragm or any similar device may be used instead of the above mentioned piston. A stem 16, centrally connected to the piston, passes through a stuffing box 17 in the cap 12 through another stuffing box 18a in the flow tubing 18 and is threaded or otherwise rigidly connected to the valve 19 which seats on the valve-seat 20. A screw 21, provided with a lock-nut 22, runs through cap 11 and is rigidly connected to a plate 23, a compression spring 24 being located between said plate and the piston 13.

A pipe 25 of a small diameter leads from the inside of the cylinder 10 near the cap 11, and opens into flow tubing 18 at a point 26. A similar pipe 27 connects the interior of the opposite end of the cylinder 10 with a pipe 28.

leading the high pressure air or gas from the source of supply C into the interior of the well casing 29. A casing-head 30 is screwed on the top of the casing 29, and a check-valve 31 is set in the line 28 on the down-stream side of the connection of the pipe 27. With such means, gas pressure in line 28 acts through pipe 27 to move piston 13 against spring 24 for unseating valve 19 and permitting fluid to flow past valve seat 20.

In order to control the valve movement further, a bracket 32 is bolted to the cap 12 and has a lever 33 hinged to it at 34. A second bracket 35 projects downwardly from said cap 12 and a spring 36 is connected to the end of said bracket 35 and the lower end of the lever 33. A stop 37 on the bracket 32 keeps the lever 33 in substantially the indicated position. A tripping mechanism is adjustably installed on the stem 16. This mechanism consists of a body 38 adjustably held by a set screw and provided with a stop shoulder 39 and a swinging finger or flap 40. By this arrangement, when the valve 19 is moved so as to seat itself, the flap 40 rises into the position shown in dotted lines when passing over lever 33 and then falls on the other side of it. On the contrary when the valve is being unseated, said flap 40 abuts against the shoulder 39, and the stem 16 will not move until a pressure is exerted sufficient to overcome the tension of the spring 36, after which the lever 33 will be moved by said tripping mechanism in its movement to the left until the flap 40 slides over said lever 33.

In operating with this automatic pressure retainer, the oil-well is flowed in the ordinary manner by the introduction of air or gas under pressure into the casing 29 through the line 28, said air or gas ejecting the oil out through the tubing 18 in the direction indicated by the arrows in Figs. 1 and 3. The air or gas under pressure enters through the pipe 27 into the part of the cylinder 10 between the piston 13 and the cap 12. The operating pressure must be greater than the tension of the spring 24 plus the pressure in the flow tubing 18, so as to compress said spring 24 and hold valve 19 open thus permitting the ejection of the liquid from the well past the valve.

If the pressure from the gas introduced from the source of supply, through the pipeline 28 into the casing 29, falls below a certain limit, which is the tension of the spring 24 plus the pressure in tubing 18, and since the tension of the spring 24 is now greater than the pressure exerted on the opposite side of the piston 13, said spring expands and moves stem 16 to seat the valve 19 on the valve-seat 20, thus closing the tubing 18 and retaining the gas pressure. In the meantime, check valve 31 closes, thus preventing the dissipation of the gas from the casing back into the pipe 28. At the same time the tripping

mechanism 38 moves to the right and the flap 40 thereof, being hinged as shown in Fig. 1, slides over the lever 33 without bringing the spring 36 into operation. When the valve 19 has reached closed position, said flap 40 hangs vertically on its hinge on the side of the lever 33 opposite to that shown in Fig. 1. Whenever the pressure in said line 28 again rises to a value slightly higher than the tension of the spring 24 plus the pressure in tubing 18, there will be a tendency to compress said spring 24 by movement of piston 13 and to unseat the valve 19. However, the flap 40 abutting against shoulder 39 of the body 38 engages the lever 33, and a substantially higher pressure must thus be created in the pipe 28, and therefore in both the casing 29 and the chamber of the cylinder 10 between the piston 13 and the cap 12, to overcome the tension of the spring 36 before said spring 36 can be elongated to permit lever 33 to move to a position which will permit the flap 40 to slide over the end of said lever 33. As long as the pressure in said casing is substantially uniform, the automatic pressure retainer here disclosed maintains the valve in open position.

The pressure changes occurring during a complete cycle of operation as just described, are diagrammatically represented in Fig. 2, which shows a typical chart of the pressure conditions in the casing. When the pressure at the source of supply drops substantially or completely (as shown by the first downward drop A of the curve), the valve 19 is closed by the action of the spring 24. When the pressure starts rising and is substantially equal or slightly greater than the normal operating pressure, the valve 19 tends to open. However, the flap 40 catches on the lever 33 and an extra pressure substantially equal to the tension of the spring 36 and represented by the quantity distance B must be created in the line 28 (and therefore in the casing 29 and in the cylinder 10) before the aforementioned valve 19 will open. The small "lost motion" of stem 16 causing the valve 19 to be slightly unseated from the valve seat 20, before the flap 40 abuts against the lever 33, has a negligible effect on the loss of pressure in the tubing 18, since the rise in pressure in the casing 29 raises the fluid in said tubing 18 so as to more than overcome the mentioned pressure loss. This small "lost motion" is required to permit the sliding of flap 40 over lever 33 during the closing of valve 19.

The lower limit of pressure at which the valve 19 will close, is regulated by compressing the spring 24 with the screw 21, the latter being held in adjusted position by the lock-nut 22. The piston 13 is preferably set loosely in the cylinder 10, and any air or gas leaking around said piston into the compartment containing the spring 24 is drained off through the line 25 into the tubing 18 thus

preventing an equalization of pressure on both sides of piston 13.

It is to be observed that the pressure changes in line 28 near line 27 are substantially identical with those occurring in casing 29 near the casing head. Obviously while the pressure changes will occur throughout the casing they will be modified by friction and leakage, and oil flow from the formation.

Fig. 3 shows a modified embodiment of the present invention, in which the tripping mechanism and the detent indicated in Fig. 1 are omitted. It is easily understood that in this embodiment the operation is substantially the same as disclosed above for Fig. 1, with the exception that the valve will open as soon as a pressure substantially equal to the normal operating pressure is created in the line leading from the source of supply to the casing.

While the method and the two devices described and shown represent desirable embodiments of the invention, nevertheless it is obvious that changes may be made without departing from the spirit of the invention. Thus, it is understood that the automatic pressure retaining device, instead of being used where the well is flowed from the tubing, may also be used in conjunction with gas-lift installations in which air or gas under pressure is introduced through the tubing and the fluid is ejected through the annular space between said tubing and the casing. Therefore, it is to be understood that the above disclosure is merely illustrative of the generic invention and is not to be considered as limiting, many variations being possible within the scope of the following claims.

I claim:

1. A method for automatically retaining pressure in a tubing in the event of a substantial or complete drop of gas pressure in the line leading from the source of supply to a casing within which the tubing is disposed, comprising cutting off flow of fluid from the tubing when the pressure in the said line drops below a certain value and simultaneously cutting off return of gas through the said line.

2. In combination a well casing, a check valve on the casing to act as casing pressure retainer, a tubing in the casing, a liquid flow control valve on said tubing, and means to automatically close and open the second valve in response to pressure variations in said casing.

3. In combination, a well casing, a well tubing depending in said casing, means to maintain an operating pressure in said casing, and an automatic pressure retainer comprising a liquid flow control valve mounted in said well tubing, means responsive to a predetermined upper operating pressure in said casing to maintain said valve in open position and means responsive to a predeter-

mined lower operating pressure in said casing to close said valve.

4. In combination, a well casing, a well tubing depending in said casing, means to maintain an operating pressure in said casing, and an automatic pressure retainer comprising a valve mounted in said well tubing, means responsive to a predetermined upper operating pressure in said casing to maintain said valve in open position, means responsive to a predetermined lower operating pressure in said casing to close said valve and means responsive to a predetermined pressure higher than said upper operating pressure to open the valve after it has been closed by the above mentioned closing means.

5. The combination of a deep well casing, a flow tubing depending within the casing, means to supply gas under pressure to the upper end of the casing, an automatic pressure retainer comprising a liquid discharge control valve in the tubing, an actuated member connected with the valve, means operatively associated with said member to move the valve toward closed position, and a connection for applying an operative force upon said member to oppose closing movement of said valve under influence of its operative means.

6. An automatic well-pressure retainer comprising a chamber, a piston movable in the chamber, a liquid flow control valve adapted to be mounted in a tubing and connected with the piston for actuation thereby, regulable means on one side of said piston adapted to actuate the piston to close the tubing valve, and means to supply pressure to the well and to the other side of said piston to oppose the action of first mentioned means.

7. An automatic well-pressure retainer comprising a chamber, a liquid flow control valve adapted to be mounted in a flow tube to cut off flow therethrough, a piston slidably mounted in the chamber and connected to the tubing valve, a regulable spring on one side of said piston, and a pipe leading gas under pressure from a source of supply to the other side of said piston.

8. In a combination with a construction according to claim 7, means for exhausting gas from the side of the piston upon which the said spring operates.

9. In combination with a construction according to claim 7, means acting in addition to and in the direction of the said spring and adapted to hold said valve in a closed position.

10. In combination a casing, a tubing in the casing, a liquid flow control valve in the tubing, a gas pressure supply pipe to the casing, means controllable by said pressure to hold the liquid flow control valve open, means to automatically close the valve when said pressure drops, and a valve on the cas-

ing to prevent a return of gas to said gas supply pipe.

11. In combination a source of gas pressure, a chamber connected to said source, a piston in the chamber, a casing connected to the source of gas pressure, a tubing in the casing, a liquid flow control valve on the tubing and connected to the piston, a connection for applying said pressure to the piston for holding said valve open, means to automatically close the valve when the pressure drops, and a check-valve on the casing to prevent a return of gas to the pressure supply.

12. In combination a source of gas pressure, a chamber connected to said source, a piston in the chamber, a casing connected to the source of gas pressure, a check-valve on the casing to prevent a return of gas from said casing to the source, a tubing in the casing, a valve on the tubing and connected to the piston, a connection for applying said pressure to the piston for holding said valve open, means to automatically close the valve when the pressure drops, and a detent on the chamber to prevent the opening of the tubing valve until a substantially higher pressure is exerted on the piston.

13. In combination a casing, a tubing in the casing, a valve in the tubing, a gas pressure supply to the casing, a check-valve on the casing to prevent a return of gas to the source of supply, means controllable by said pressure to hold the valve open, means to automatically close the valve when the pressure drops, and an auxiliary control means on the chamber and valve to prevent the opening of the tubing valve until a substantially higher pressure is exerted on the piston.

14. In combination a casing, means to supply gas pressure to the casing, a check-valve on the casing to prevent pressure loss through the supply means, a tubing in the casing, a valve on the tubing, and means to automatically close the valve, when a predetermined lower pressure is in the supply means, and open it above said pressure.

15. In combination a casing, means to supply gas pressure to the casing, a check-valve on the casing to prevent pressure loss through the supply means, a tubing in the casing, a valve on the tubing, means to automatically close the valve below a predetermined pressure in the supply means, and an auxiliary control means to prevent the opening of said valve until a substantially higher pressure is exerted on the piston.

16. In combination a casing, means to supply gas pressure to the casing, a check-valve on the casing to prevent pressure loss through the supply means, a tubing in the casing, a liquid flow control valve on the tubing, actuating means connected to the valve, a pressure by-pass from said supply means to move the actuating means and valve when pressure ex-

ceeds a predetermined value, and means to return the valve when pressure falls below said predetermined value.

17. A method for automatically regulating the pressure in an oil well eduction tubing connected with a gas induction pipe in which a gas pressure is maintained from a source of supply, comprising the step of interrupting flow of fluid from the tubing by closing the liquid flow valve thereon when the pressure from the source of supply drops below a certain value, and the step of restoring flow of fluid from the tubing when the pressure from said source of supply rises above a certain value.

18. A method for automatically regulating the pressure in a liquid eduction tube leading from a liquid supply, to which tube gas under pressure is supplied from a source, comprising controlling flow from the eduction tube in response to pressure variations in said source of gas supply.

19. A method for automatically regulating the pressure in a liquid eduction tube leading from a liquid supply, to which tube gas under pressure is supplied, comprising permitting flow from the eduction tube when said pressure exceeds a certain value, and interrupting the flow from said eduction tube when the gas pressure drops below a certain value.

20. A method for automatically regulating the pressure in a liquid eduction tube leading from a liquid supply, to which tube gas under pressure is supplied, comprising interrupting the flow from the eduction tube when gas pressure in the source of gas supply drops below a certain value, and permitting flow from said eduction tube when said pressure exceeds a certain value.

21. In combination a deep well casing, a tubing therein, a liquid flow valve in the tubing, a gas pressure supply pipe leading to the casing, means controllable by said pressure to hold the valve open, and means to automatically move the valve toward closed position when said pressure drops.

Signed at Los Angeles, in the county of Los Angeles, and State of California, this 5th day of July, A. D. 1929.

JACOB J. KOGAN.
